MILES S. PRENTICE, OF ROCKFORD ILLINOIS.

Letters Patent No. 67,581, dated August 6, 1867.

IMPROVED WASHING MACHINE.

The Schedule recited is in these Letters Patent and making part of the same.

TO ALL WHOM IT MAY CONCERN:

Be it known that I, MILES S. PRENTICE, of Rockford, in the county of Winnebago, and State of Illinois, have invented a new and useful improvement in Washing Machines; and I do hereby declare that the following is a full, clear, and exact description thereof, which will enable others skilled in the art to make and use the same, reference being had to the accompanying drawings, forming part of this specification, in which—

Figure 1 is a top or plan view of my improved washing machine, the top or cover being raised.

Figure 2 is a vertical longitudinal section of the same, taken through the line x x fig. 1.

Similar letters of reference indicate like parts.

My invention has for its object to furnish an improved washing machine simple in construction, easily operated, and which will do its work quickly and thoroughly, and without injury to the fabric and it consists in the combination of the bent or bell-crank levers with the arms of the beater or plunger, with the box or tub; in the combination of the self-adjusting check-board with the beater or plunger and with the box or tub; and in the combination of an ordinary wash or rubbing-board with the arms of the beater the whole being constructed and arranged as hereinafter more fully described.

A is the box or tub, which is supported upon legs B of convenient length. The sides a¹ of the box or tub A are vertical, and its ends a² incline outward, as shown in fig. 2. The bottom a³ inclines upward from end to end of the machine, as shown in fig. 2. C is the beater, the face of which is grooved or corrugated, as shown in the drawings, and which is rigidly attached to the inclined ends of the arms c'. D are two bent or bell-crank levers, which are connected at their ends and angles by the rods d¹ d² d³. The lower ends c' of the levers are pivoted to the tub by placing the rod d¹ that connects the lower ends of said levers in a groove formed in the angle at the higher end of the bottom board a³. The angles of the levers D are pivoted to the ends of the arms c' of the beater C by the connecting-rod d², which passes through the ends of the said arms. The upper connecting-rod d³ serves as a handle for operating the beater or plunger. E is an ordinary washing or rubbing-board, which is securely and permanently attached to the upper edges of the beater-arms c', so as to be in convenient position, when the beater is drawn back, for being used to rub any parts or spots of the clothes that may be more than ordinarily soiled. F is a self-adjusting check-board, which is placed in the box or tub in front of the beater C, and the lower edge of which is bevelled off to correspond with the inclination of the face of the beater C. The board F works up and down along the end of the tub A, and adjusts itself to the amount of clothes being washed, working at a higher elevation with a larger quantity than it does with a smaller quantity, so that the pressure of the beater upon the clothes may always be uniform. It will be observed that when being used the bent levers D and arms c' of the beater C act as toggle-joints; that is to say, with a constantly increasing power, as the beater is forced farther and farther forward. G is the cover of the box or tub A, which, when closed down, converts the machine into a convenient work-table, and which, when turned back into a horizontal position, and properly supported, forms a convenient table for sorting the clothes to be washed.

What I claim as new, and desire to secure by Letters Patent, is—

1. The combination of the bent or bell-crank levers D with the arms c' of the beater C, and with the box or tub A, to which their lower ends are pivoted, substantially as herein shown and described, and for the purpose set forth.
2. The combination of the self-adjusting check-board F with the beater or plunger C, and with the box or tub A, substantially as herein shown and described, and for the purpose set forth.

MILES S. PRENTICE.
